US0D1027878S

(12) **United States Design Patent** (10) **Patent No.:** **US D1,027,878 S**
(45) **Date of Patent:** **** May 21, 2024**

(54) **SWITCH**

(71) Applicant: **Shiyong Huang**, Ganzhou (CN)

(72) Inventor: **Shiyong Huang**, Ganzhou (CN)

(**) Term: **15 Years**

(21) Appl. No.: **29/854,905**

(22) Filed: **Sep. 29, 2022**

(51) **LOC (14) Cl.** **13-03**

(52) **U.S. Cl.**

USPC **D13/158**

(58) **Field of Classification Search**

USPC D13/3, 30-32, 38, 107, 108, 110, 137, D13/137.1, 137.2, 137.4, 138.1, 138.2, D13/139.1, 139.2, 139.3, 139.4, 139.5, D13/139.6, 139.7, 139.8, 146, 151-154, D13/158-162, 162.1, 163-169, 171-179, D13/184, 199; D8/350-353

(57) **CLAIM**

The ornamental design for a switch, as shown and described.

DESCRIPTION

FIG. 1 is a first perspective view of a switch showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the switch that form no part of the claimed design.

1 Claim, 8 Drawing Sheets
